UNITED STATES PATENT OFFICE.

DEAN E. BASKERVILLE, OF DETROIT, MICHIGAN, ASSIGNOR TO DODGE BROTHERS, OF DETROIT, MICHIGAN, A CORPORATION OF MICHIGAN.

SHEET-METAL PILLAR-COVER.

1,288,371.

Specification of Letters Patent. Patented Dec. 17, 1918.

Application filed September 28, 1917. Serial No. 193,660.

To all whom it may concern:

Be it known that I, DEAN E. BASKERVILLE, a citizen of the United States, residing at Detroit, Michigan, have invented certain 5 new and useful Improvements in Sheet-Metal Pillar-Covers, of which the following is a clear, full and exact description.

This invention relates to a sheet metal cover for the pillars of inclosed automobile 10 bodies.

Owing to the peculiar shape of these pillars it has been found impracticable to construct them of anything but wood, and as in many cases they extend above the sheet metal panels of the lower part of the body, a considerable portion of them is exposed to the weather. This exposed wooden surface is objectionable for several reasons. First, because it is more affected by the action of 20 the elements than the metal surface. Second, a greater number of coats of paint are required to produce a satisfactory finish than is the case with metal surfaces. Third, the combination of metal and wooden surfaces in a body produces a lack of uniformity in appearance.

One of the objects of this invention is consequently to provide a sheet metal pillar cover which may be easily and cheaply manufactured and which presents a neat appearance. Another object is to provide such a cover which may be easily attached and which is constructed so that the attaching means are not visible.

These being among the objects of the present invention, the same consists of certain features of construction and combinations of parts to be hereinafter described and then claimed with reference to the accompanying drawings which illustrate a suitable embodiment of the invention having the above and other objects in view.

Figure 1 is a vertical elevation of the pillar cover in place upon an automobile body, as seen from the side.

Fig. 2 is a cross section on the line 2—2 of Fig. 1.

Fig. 3 is an elevation similar to Fig. 1 but with the pillar cover removed.

Fig. 4 is an elevation of the pillar cover separated from the other parts.

Fig. 5 is an elevation looking outward from the center line of an automobile body and showing the inner edge of the pillar cover.

Fig. 6 is a cross section on the line 6—6 of Fig. 3.

Fig. 7 is a cross section on the line 7—7 of Fig. 4.

Fig. 8 is a cross section on the line 8—8 of Fig. 4.

Fig. 9 is a side elevation of the forward part of an automobile body showing the pillar cover in place.

Referring to the drawings, the pillar cover 11 has in general a curved cross section to conform to the lines of the body and is provided with attaching flanges at both vertical edges. The flange 12, which follows the side of the opening in the front end of the body filled by the windshield, is provided with countersunk holes and is attached to the pillar by the wood screws 13. These screws, however, are not visible as the frame of the windshield 21 abuts against this flange and covers the screws. To improve the appearance at the junction of the windshield frame and the pillar, the bead 14 is provided which covers any crack which might exist due to the windshield not fitting 80 the opening exactly. At the rearward edge of the pillar cover the fastening means is entirely concealed and consists of the strip 15 which coöperates with a notched flange 16 integral with the cover. The strip 15 is secured to the wooden pillar by the wood screws 17 and is provided with projections 18 formed at intervals upon its rearward edge which are offset from the main portion of the strip so as to provide a space for receiving the notched flange 16 of the cover between the wooden pillar and these projections. At the lower end of the cover a rounded edge 22 may be provided to improve the appearance and make it easy to 95 get a good fit between the pillar and the cover.

In applying the cover it is placed against the pillar in a position somewhat lower than its permanent one with the projections 18 of the strip 15 registering with the corresponding notches 19 in the rearward flange of the cover. The cover is then slid upward with the flange 16 under the corresponding projections 18, which are so shaped that they exert a considerable pressure holding the flange against the pillar. The upward movement of the cover is continued until stopped by the roof of the body when it is secured in position by the wood screws 13 through the 110

flange 12. To permit of this method of applying the cover, it is necessary to stop the flange 12 short of the lower edge of the cover as shown at 20 so that the cover may be placed tightly against the pillar and the upper edges of the various sections of the flange 16 introduced under the projections 18 while the cover is considerably lower than when in its final position. The absence of the flange at the lower end of the cover does not, however, leave the wooden pillar exposed as the frame of the windshield covers this surface.

Beyond the rearward edge of the pillar cover a depressed area or reveal is left at the side of the window opening. The surface of the pillar at the reveal may be covered by the sheet metal piece 23, one edge of which lies in the groove for the window and the other edge of which is concealed by the pillar cover. This strip may be fastened by screws at the forward edge and will not require any fastening at the rearward edge if properly shaped.

It is obvious that this invention is susceptible of modifications as parts may be omitted, parts added and parts substituted without departing from the spirit and scope of the invention as expressed in the claims.

What I claim as new is:

1. In combination with an automobile body and wooden pillar, a sheet metal cover for said pillar embracing two sides thereof, and concealed means for locking said cover to said post, comprising coöperating means respectively on said pillar and on the underside of said cover arranged to interlock upon longitudinal movement of said cover into covering relation to said pillar.

2. In combination with an automobile body and wooden pillar, a sheet metal cover for said pillar embracing two sides thereof, and means located beneath said cover and brought into interlocking relation thereto by

relative longitudinal movement of said means and said cover for locking said cover to said pillar.

3. In combination with an automobile body and wooden pillar, a sheet metal cover for said pillar embracing two sides thereof, a notched flange turned under but spaced from said cover, means secured to said pillar and having projections arranged to enter between the notches of said cover when said cover is first placed in position, said means and said cover being relatively movable longitudinally to bring said projections into interlocking relation with the flange, and means for securing said cover to said pillar at its edge remote from said flange.

4. A sheet metal cover for an automobile body pillar comprising a curved main portion and integral attaching flanges, one of said flanges standing approximately normal to said main portion and the other of said flanges lying approximately parallel to said main portion and being provided with a plurality of notches, and an attaching strip engageable with said last mentioned flange and having notches complementary to those on said cover.

5. In combination with an automobile body, a wooden pillar, a sheet metal cover for said pillar, comprising an elongated main portion and a flange lying approximately parallel to said main portion and connected thereto by a cylindrical surface of relatively small radius of curvature; concealed attaching means engaging with said flange and a stamping applied along one edge of said pillar and extending under said cover at said flange to form a reveal.

Signed at Detroit Michigan this 24th day of September 1917.

DEAN E. BASKERVILLE.
